(No Model.)

W. B. FLEMING.
POUCH PNEUMATIC FOR PIPE ORGANS.

No. 594,391.

Patented Nov. 30, 1897.

UNITED STATES PATENT OFFICE.

WILLIAM B. FLEMING, OF DETROIT, MICHIGAN.

POUCH-PNEUMATIC FOR PIPE-ORGANS.

SPECIFICATION forming part of Letters Patent No. 594,391, dated November 30, 1897.

Application filed February 6, 1897. Serial No. 622,242. (No model.)

To all whom it may concern:

Be it known that I, WILLIAM B. FLEMING, a citizen of the United States, residing at Detroit, county of Wayne, State of Michigan, have invented a certain new and useful Improvement in Pouch-Pneumatics for Pipe-Organ; and I declare the following to be a full, clear, and exact description of the invention, such as will enable others skilled in the art to which it appertains to make and use the same, reference being had to the accompanying drawings, which form a part of this specification.

My invention relates to certain new and useful improvements in pouch-pneumatics for pipe-organs; and it consists of the construction, combination, and arrangement of devices hereinafter described and claimed, and illustrated in the accompanying drawings, in which—

Figure 1 is a vertical section of parts of an organ mechanism disclosing my invention. Fig. 2 is a cross-section of the pneumatic on the line 2 2, Fig. 1.

The aim of my invention is to provide pouch-pneumatics for pipe-organs that shall be simple and economical in construction and efficient in their operation.

I carry out my invention as follows:

In the drawings, A represents a pallet or fresh-wind box, which, it will be understood, is continually supplied with air.

B is a wind-chest.

C is a bottom board constructed with a channel C'.

D is a top board above the wind-chest B. Within the wind-chest B are located my improved pouch-pneumatics E.

F is a chest-bar constructed with an exhaust-channel F', communicating with an interior adjacent pouch-pneumatic and with the channel C'. Said chest-bar is also constructed with a wind-channel F², communicating with the wind-chest B and an adjacent pipe G, the communication of the channel F² with the wind-chest being governed by a pallet or valve E'. The pallet-box A communicates with the channel C' through an opening at A'. The channel C' exhausts through an opening at C². A valve H controls the communication of the pallet-box A through the opening A' with the channel C' and a

valve H' controls the communication of the exhaust-channel through the opening C². Said valves H and H' are mounted on a stem 55 H², mounted on a lever J, and connected, as by rod J', with a corresponding key on the keyboard, the key not being shown. The lever J is raised and held in normal condition by any suitable spring K.

The pouch-pneumatic is constructed of a block E², cut away intermediate its ends, forming shoulders e and e'. Over the cut-away portion of the block is secured a flexible strip E³, the block also being dished or cut away 65 intermediate said shoulders to allow the flexible strip E³ to yield thereinto. Between the body of the block and the flexible strip is thus formed a wind-chamber b. Intermediate the shoulders e and e' and between the 70 chest-bar F and flexible strip E³ is formed a chamber E⁴ within the chest B and communicating therewith.

E⁵ is any suitable spring bearing upon the pallet E' to set the pallet firmly when wind-pressure is equalized. This spring may conveniently be made of a piece of wire run in through one end of the block E², as shown, its inner end engaging in a recessed bracket e².

E⁶ represents the forks by which the pouch-pneumatic is secured upon the channel-board F by means of screws e³.

It will be understood that each manual has its own wind-chest and that there are as many wind-chests as there are stops to the organ, 85 there being as many pneumatics in each wind-chest as there are keys on the organ.

The operation of the devices hereinbefore described is as follows: The spring K normally holds the exhaust-valve H' closed and 90 the valve H open, permitting the air to pass from the pallet-box through the channels C' and F' into the pouch-pneumatic, which will of course close the pallet E' and shut off wind from the pipe G. When a given key is depressed, thereby drawing down lever J, the valve H is closed, cutting off wind from passing from the pallet-box into the channel C' and opening the channel C' through the port C², whereby wind will be permitted to exhaust from the pouch E, in which event the pallet E' will be lifted by the wind-pressure in the wind-chest B, collapsing the pouch-pneumatic, whereby the wind may pass from

the wind-chest B through the channel F² to the pipe.

What I claim as my invention is—

1. The pouch-pneumatic constructed of a block cut away intermediate its extremities, a flexible strip secured upon the cut-away portion of the block and provided with a pallet, and a spring bearing upon said pallet, said pouch-pneumatic provided with a wind-channel communicating therewith, substantially as set forth.

2. The pouch-pneumatic constructed of the block F² cut away intermediate its ends, and a flexible strip secured upon said block intermediate its ends, a pallet connected by said strip, and a spring bearing upon said pallet, said pouch-pneumatic having an air-passage communicating with the interior thereof substantially as set forth.

3. In a pipe-organ the combination of the wind-chest B, and chest-bar F provided with air-passages F' and F², and a pouch-pneumatic located in the wind-chest, said pouch-pneumatic formed with an interior air-chamber communicating with the channel F', with a flexible strip E³, a pallet carried by said flexible strip and a spring bearing upon said pallet, substantially as set forth.

4. In a pipe-organ the combination with a

wind-chest B and a chest-bar F provided with air-passages F' and F², a pipe communicating with the wind-chest, and a pouch-pneumatic located in the wind-chest, said pneumatic formed with an interior air-chamber communicating with the channel F', with a flexible strip E³, a pallet E' controlling the communication of the wind-chest with the pipe, and a spring bearing upon said pallet, said wind-chest having a wind-chamber E⁴ under said flexible strip, substantially as described.

5. The combination with a wind-chest of an independent and separably-removable pouch-pneumatic for each key on the organ, said pneumatic constructed of a block formed with a wind-chamber b, a flexible strip forming one side of said chamber, and a pallet carried by said strip, said pneumatic provided with an air-passage leading into said chamber, and said wind-chest opening underneath said flexible strip, substantially as described.

In testimony whereof I sign this specification in the presence of two witnesses.

WILLIAM B. FILEMING.
